3 Claims. (Cl. 93—53)

1

This invention concerns improvements in or relating to devices for opening shells of slide and shell cartons of the kind used in automatic packing machines, for example, cigarette packing machines.

An object of the invention is to provide a device of this kind which is readily adjustable so as to deal with shells of various heights, that is shells for packets of various thicknesses.

It is common to open a flattened shell, for example, for a cigarette carton, by subjecting it to pressure at the two edges of the flattened shell. The shell is pressed at one edge by a movable member such as a reciprocating feed tooth which also serves to move the shell to the opening position and at the opposite edge by another movable member which presents an interior angle to the edge of the shell and at a higher level so that the flattened shell, just before opening commences, lies at an angle to a horizontal plane or surface along which it is moved to the opening position. The guiding of the leading edge of the shell upwards to the corner of said angle is effected by an angular ramp or guide and the present device is of this kind.

In such devices as hitherto constructed the ramp is commonly a hinged plate and not only is hinging undesirable in view of dirt and wear but such a device can only handle shells of substantially the same height or packet thickness.

According to the present invention there is provided a shell opener of the kind referred to comprising a ramp inclined at a fixed angle and means whereby the ramp surface and the shell may be brought into contact in the initial stages of the opening operation and withdrawn from contact as opening proceeds. Thus the ramp may be movable into and out of the part of the opener where the shell is located or a fixed ramp may be used and the opener so operated that at times the ramp is within said part of the opener and outside said part at other times.

Further according to the invention there is provided a shell opener of the kind referred to comprising a member of substantially L-shaped cross-section which is arranged with an arm of the L in a vertical position so that the other member is horizontal and an interior angle is provided for engaging the shell, said vertical member being fixed to an operating member movable during shell opening at an angle of 45° with respect to a horizontal plate forming the base of the shell opener and one or more

2

ramps extending from said horizontal plate and disposed at 90° to the path of movement of the operating member the ramps passing through holes in the L member so arranged that the latter can only move down towards the horizontal plate to a position determined by said ramps which are then directed to the corner of the interior angle.

The L-shaped member may be adjustable on the operating member so that the height of the horizontal member of the L from the base plate of the opener can be adjusted to render the device useful for shells of various heights and with the construction set forth in the previous paragraph it will be seen that as the L member is adjusted to a new position (e. g. raised) it will, when in the lowest position it occupies during the shell opening operation, be arrested by the ramps which will then be directed to the corner of the interior angle.

The device may comprise pressers operating on opposite sides of the flattened shell viz. one above and one below the shell and located respectively near the L member and the other movable member (such as a feed tooth) such pressers being well known in the art.

One way of carrying the invention into effect will be described with reference to the accompanying drawings in which:

Figure 1 is a front elevation of part of a packing machine embodying the invention.

Figure 2 is a side elevation of Figure 1.

Figures 3, 4 and 5 are fragmentary views illustrating the operation of the device.

Referring to the drawings a shell S is fed out of a magazine and delivered on to the surface of the machine bed 1. The manner of feeding the shell forms no part of the present invention but it may be mentioned that the shell can be fed out by a reciprocating tooth or by any suitable suction device. In the case of the machine of which the devices illustrated form part, the shell is brought down by suction from a magazine and moves down in the direction of the arrow, Figure 1, to the bed 1 at the position shown whereupon a reciprocating pusher 2 moves it to the right by a distance about equal to the width of the flattened shell. At the time when the shell is deposited in the position shown, an oscillating pusher tooth 3 is at the other end of its movement from that shown in Figure 1 and as the tooth swings to the right, the tooth pushes the shell, which has been moved along the bed by the pusher 2 in the meantime, sideways into the opening device generally indicated

by the reference 4. At one end of the opening device are a pair of fixed ramps 5 whose operative faces are at an angle of 45° to the surface of the bed 1.

Beneath the bed 1 is fixed a guide 6 located at an angle of 45° to the plane of the bed 1 so that there is an angle of 90° between the operative faces of the ramps 5 and the guide 6. A slide 7 is movable up and down the guide by cam mechanism described later, moving up the guide for shell opening and down it during shell feeding. The upper part of the slide extends horizontally at 8. To the horizontal part is fixed an angle bracket 9 to which is attached an L-shaped piece 10 about to be described. One limb 10A of the L is located in a vertical plane and adjustably fixed to the vertical part of the angle bracket. The limb is also slotted at 11 to provide clearance for the ramps 5, see Figure 2. The other member 10B of the L is relatively short and is located in a horizontal plane, i. e. parallel to the bed 1 and thus the member provides an interior angle or corner adapted to engage that side of the shell opposite to the side engaged by the oscillating tooth 3. The under-surface of the extremity of the horizontal member 10B of the L is curved or beveled as shown in Figure 1 to form a lead which tends to direct shells into the corner when they fail to move immediately into said corner. It will also be seen from Figure 1 that this inner corner of the L is nicked or undercut to provide a proper location for the corner of the shell.

In setting up the device for a particular shell the slide 7 is moved to its top position on the guide 6 and then the L member is adjusted until it contacts with an open shell lying inside the opener. Figure 5 shows an opened shell with the slide 7 at its top position and the L touching the top of the shell. It will be seen that if, say, a smaller shell is to be dealt with, it is only necessary to bring the machine parts to this position and then to lower the L by its adjustment until it touches the top of the shell. Referring to Figures 3 to 5, as the slide moves to the advanced position, the L member passes, in moving towards the pusher 2, beyond the ramps 5 which are thereafter outside of the shell opener. As the slide moves down when a new flattened shell is to be fed into the opener the horizontal member of the L moves down towards the bed 1 but remains parallel thereto while the vertical member moves down through the bed 1, remaining vertical thereto and moving away from the pusher 2. During this movement the L member moves past the ramps so that at the end of the movement the ramps are again inside the opener and directed towards the interior angle or corner of the L.

The operation of this general kind of shell opener is well known and only a brief description seems necessary. The pressure of the tooth 3 and L member, causes the shell to open and to ensure correct opening and prevent displacement of the shell from its position in the L member. There are provided top and bottom pressers 12 and 13 which bend the shell into shallow arcs and ensure that it opens instead of merely bowing. Thus as a new shell is moved into the opener 4 by the tooth 3 its leading edge slides up the ramps 5 and abuts the interior corner of the L. Then the L-shaped member 10 advances towards the tooth 3 simultaneously rising with respect to the bed 1, and the combined pressure of the two movable members (L member and

tooth), causes the shell to open, the full opening becoming possible with the disappearance of the ramps from the inside of the opener.

The forward position of the L member is substantially constant for shells of all heights within the capacity of the device but the rear position varies with the adjustment because the lower the L is set on the slide the sooner its movement is checked by the abutting of the L and the 10 ramps.

The devices for operating the parts will now be described.

A shaft 14 has a crown cam 15 affixed thereto and beyond the cam 15 is a disc cam 16 and a 15 bevel gear wheel 17 is fixed to the end of the shaft. A similar bevel gear wheel 18 is fixed to a vertical shaft 19 at the top of which is another bevel gear wheel 20 engaging with a similar wheel 21 fixed on a shaft 22 to which cams 23 and 24 are fixed.

The crown cam 15 engages a roller 25 on the end of a lever 26 pivoted to the machine bed at 27 and to the top of this lever is fixed the tooth 3.

The cam 23 on the shaft 22 engages a roller 28 on a double armed lever 29 pivoted to the bed at 30 and the other end of the lever is curved round as shown and carries a roller 31 which presses on the end of the slide 7. A spring 32 housed in the guide 6 moves the slide on the return movement. The upper end of the double armed lever has a slot 33 concentric with a shaft 22 and along which the roller 28 can be shifted.

It will be seen that the nearer the roller 28 is to the pivot 30 the greater the stroke of the slide 7 and by this adjustment the stroke can be set for any thickness of shell. It will be seen that the collapsed width of a thin shell (e. g. for five cigarettes) is less than that of a shell for ten cigarettes of the same kind, and therefore as the movements of the tooth 3 are the same under any circumstances the leading corner of a thin shell would be later in contacting the interior corner of the L member. Once a collapsed shell is nipped between the tooth and the angle of the L member it opens with extreme rapidity.

It is therefore necessary that the movement of the L member should be faster for thin shells so as to meet the shell at a given position of the tooth 3, otherwise the ramps would be in the way of the opening shell. The above described adjustment of the roller thus caters for all shells and under any circumstances the instant the collapsed shell is first nipped between the tooth 3 and the interior corner of the L member is substantially constant.

The cam 24 on the shaft 22 engages a roller 34 at one end of a double armed lever 35 pivoted at 36 to a bracket 37 fixed to the bed. The other arm of the lever is formed into a flat bracket 38 to which is attached a plate 39 whose free end constitutes the top presser 12. To the lever 35 is connected a link 40 whose lower end is pivoted at 41 to a double-armed lever 42 pivoted to the bed at 43. To the other arm of this lever is fixed the bottom presser 13. Thus the two pressers operate together.

After the shell has been opened, a filled slide 70 is inserted in the shell and in the machine shown, this is done in a well-known manner, which will be briefly described.

At the left-hand side of Figure 2 is a mouth-piece 44, through which the slide is pushed by an overhead conveyor (not shown). Before this

occurs, the open shell is pushed on to the mouthpiece so that the latter functions as a kind of funnel. The shell is pushed on the mouthpiece by an oscillating pusher 45 pivoted at 46 to the bed and beyond the pivot is a lever 47 having a roller 48 at its end which engages the disc cam 16. After the shell has been pushed on the mouthpiece, the pusher acts as a stopper or abutment while the slide is being inserted and gives way just as the slide is home.

In another construction, which, in view of the foregoing description, does not appear to need illustration, the ramps may be carried on a member slidable along the table and moving into and out of the shell opening position. The movement of the L member is then not necessary, but it is set in a fixed position embracing the height and one side of the open shell.

As the leading edge of the flat shell, which is pushed forward by the tooth, arrives at the corner of the L, the ramps recede and disappear behind the vertical face of the L.

This method is not so desirable owing to the extreme angle of the shell relative to the pushing tooth. This would impair opening of the shell, especially shells with a small body width.

What I claim as my invention and desire to secure by Letters Patent is:

1. A device for opening flattened shells of slide and shell cartons solely by the application thereto of external pressure, said device comprising, in combination, a generally horizontal support for a flattened shell, a fixed ramp inclined upwardly and away from said support, a presser member supported for movement toward and into engagement with one corner of a flattened shell resting on said support to effect displacement of the shell toward said ramp, whereby the opposite corner of the shell is caused to slide

upwardly on said ramp, a second and angularly shaped presser member having a generally horizontal and a generally vertical leg presenting an interior angle of 90° to the said opposite corner of said shell, and means supporting said second presser member for movement transversely of and beyond said ramp to engage and apply pressure to said opposite corner of the shell to effect full opening of the shell to rectangular cross-section.

2. A device as claimed in claim 1 including devices mounting said second presser member for generally vertical adjustment on its supporting means to accommodate the device to the handling of shells of varying height.

3. A device as claimed in claim 1 in which the supporting means for the second presser member comprises an operating member, mechanism for reciprocating said operating member, and means cooperating with said mechanism to alter the length of the stroke of said operating member to accommodate the device to the opening of shells of different thickness.
